HAND GREASE GUN

Chester Dorn, Spencer, Iowa, assignor to Superior Manufacturing Company, Spencer, Iowa

Filed June 15, 1970, Ser. No. 23,468

Term of patent 14 years

Int. Cl. D8—02

U.S. Cl. D8—14.1

Fig. 1

Fig. 2

Fig. 3

Fig. 4

Fig. 5

Fig. 6

FIG. 1 is a perspective view of a hand grease gun embodying my new design;

FIG. 2 is an elevational view taken from one side thereof, the opposite side being a mirror image of the side shown;

FIG. 3 is a rear elevational view thereof;

FIG. 4 is a front elevational view thereof;

FIG. 5 is a top plan view thereof; and

FIG. 6 is a bottom plan view thereof.

I claim:

The ornamental design for a hand grease gun, substantially as shown and described.
